DEVICE FOR CLEANING FLOORS

Edwin A. Beyer, Buffalo, N. Y.

Application June 20, 1945, Serial No. 600,595

6 Claims. (Cl. 214—26)

1

This invention relates generally to the art of handling solids, and particularly to new apparatus for use with an open hearth charging machine in cleaning solids from the charging floor in front of an open hearth furnace.

During the operation of an open hearth furnace various solids are charged into the furnace and some of those solids are spilled onto the charging floor in front of the furnace. Heretofore such solids have been cleared away by hand shoveling which necessitated the expenditure of considerable labor. The present invention provides apparatus which can be operated by the charging machine to clear away substantially all such solids without the expenditure of any substantial amount of hand labor.

Altho the herein illustrated and described embodiment of the present invention is especially suited to use with a charging machine, it will be understood that other devices embodying the invention may be used with other types of actuating apparatus which are capable of shifting such a device to scraping, carrying, or dumping positions and of propelling it during the loading operation. For example, the attaching means at one end of the box herein illustrated may be altered to fit a suitable arm on an automobile, tractor or other wheeled vehicle for use in scraping up solids and transporting them to a place where they are to be dumped.

The present invention will be better understood by those skilled in the art from the following description and the drawings which accompany this specification and in which,

Figure 1 is a fragmentary perspective view showing a box constituting one embodiment of the invention and adapted for use with an open hearth charging machine;

Figure 2 is a top plan view of the box of Fig. 1; Figure 3 is a cross-sectional view taken on line 3—3 of Fig. 2;

Figure 4 is an elevational view of the right-hand end of the box of Fig. 2;

Figure 5 is a lefthand elevational view of the box of Fig. 2; and,

Figure 6 is a side elevational view of the scraper side of the box of Fig. 2.

Figure 1 shows the front of an open hearth furnace 1, a charging floor 2 having rails 3 for charging box cars and one rail 4 of a charging machine track. The peel 5 of a charging machine (not shown) is connected at its free end to a box 6 for scraping up solids on floor 2 and transporting them to a place of disposal, for example, dirt box 7.

2

The box 6 of Fig. 1 is shown in more detail in Figs. 2 to 6 inclusive. This box is open-topped and has a bottom 10, a low end 11, a high end 12, a low side 13, and a high side 14. The high end 12 is provided with a wall 15 spaced apart therefrom and slotted as at 16 to receive the free end of peel 5 and is also provided with holes 17 to receive pins at the end of the peel. When the free end of the peel 5 is inserted between the end wall 12 and spaced wall 15 and the pins are inserted in holes 17, the box may be lifted, rotated and moved endwise by the peel and also moved sidewise when the charging machine runs along its rails.

Strengthening ribs 20 extend along the outer surface of bottom 10 and side 14 substantially parallel to ends 11 and 12 of the box. Each of these ribs merges into an offset flange 21 which extends along the upper edge of side wall 14. A corresponding offset flange 22 extends along the upper edge of the low end 11 of the box and another similar offset flange 22 extends along the upper edge of the high end 12 of the box. The ribs 20 and the adjacent ends of flanges 21 define spaces 23 therebetween for a purpose presently to appear.

It will be noted that the upper edge of side 14 of the box is inclined at an acute angle to the bottom 10 of the box and that the low and high ends of the box have integral wings 25 and 26, respectively, which extend part way across the ends. A scraper blade 27 is disposed on the inclined upper edge of side 14 of the box and has ends 28 which extend along the ends of the box. Blade 27 has substantially parallel longitudinal edges, one of which bears against the upper edge of side 14 of the box while the side surface of the blade bears against the inner surface of offset flanges 21. Similarly, the ends 28 of the blade rest on the upper edges of ends 11 and 12 and bear against flanges 22. This blade with its ends constitutes extensions of side 14 and ends 11 and 12 of the box. Blade 27 has exterior, integral, ribs 29 which extend downwardly below its lower edge, lie in the spaces 23 parallel and adjacent to ribs 20, and may be detachably connected to those ribs, as by bolts and nuts 30. Additionally, bolts 31 detachably secure the blade to flanges 21 and 22.

When the box of Figs. 2 to 6 inclusive is mounted on the peel 5 of a charging machine, the free edge of blade 27 may be brought into contact with the charging floor 2 and the box may be propelled along the floor with the result that solids on the floor will be scooped into the box.

55 The box may be rotated into an upright position.

and the solids therein may either be charged into the furnace in the ordinary charging box manner or may be dumped into box 7.

Having thus described my invention so that others skilled in the art may be able to understand and practice the same, I state that what I desire to secure by Letters Patent is defined in what is claimed.

What is claimed is:

1. A floor scraping device comprising an open topped box having a bottom, sides and ends, ribs parallel to said ends and projecting outwardly from the bottom and one side of the box, a blade attached to said ribs and bearing on the top edges of said side and the ends of said box, and means at one end of the box for connecting it to the peel of a charging machine.

2. A floor scraping device comprising an open topped box having sides and ends, ribs parallel to said ends and projecting outwardly from one side of the box, offset flanges extending from each of said ribs along the upper edge of said rib-bearing side of the box, a blade bearing against the upper edge of said side and against said flanges, ribs extending from said blade along the ribs of said side and attached thereto, and means at one end of the box for connecting it to the peel of a charging machine.

3. A floor scraping device comprising an open topped box having a bottom, sides and ends, a blade attached to the box and constituting an extension of the ends and one side of the box, said blade having a free edge disposed at an acute angle to said bottom of the box, and means at one end of the box for connecting it to the peel of a charging machine.

4. A floor scraping device comprising an open topped box having a bottom, sides and ends, one of said sides having an upper edge inclined at an acute angle to said bottom of the box, a blade attached to the box and constituting an extension of the ends and said side of the box, said blade having a free edge substantially parallel to the upper edge of said side of the box, and means at one end of the box for connecting it to the peel of a charging machine.

5. A floor scraping device comprising an open topped box having a bottom, sides and ends, one of said sides having an upper edge inclined at an acute angle to said bottom of the box, ribs projecting outwardly from said side parallel to said ends of the box, offset flanges along the upper edge of said side, a blade having parallel longitudinal edges, and ribs extending beyond one of its edges to lie beside the ribs of said side of the box when the blade bears against the upper edge of said side and said offset flanges, means connecting said ribs of the blade to the ribs of the box side, and means at one end of the box for connecting it to the peel of a charging machine.

6. A floor scraping device comprising an open topped box having a bottom, sides and ends, exterior reinforcing ribs integral with said bottom and one side and parallel to said ends, a scraper blade detachably connected to the ribs of said side of the box, said blade constituting an extension of said side and having a free edge inclined at an acute angle to the bottom of the box, and means integral with one of said ends for connecting said box to the peel of an open hearth charging machine.

EDWIN A. BEYER.
